STANLEY W. HAYES, OF RICHMOND, INDIANA, ASSIGNOR TO HAYES TRACK APPLICATION COMPANY, OF RICHMOND, INDIANA, A CORPORATION OF INDIANA.

HAND-OPERATED DERAIL.

1,420,426.

Specification of Letters Patent. Patented June 20, 1922.

Application filed January 23, 1919, Serial No. 272,671. Renewed November 28, 1921. Serial No. 518,432.

To all whom it may concern:

Be it known that I, STANLEY W. HAYES, United States citizen, residing in the city of Richmond, county of Wayne, Indiana, have 5 invented the following described Improvements in Hand-Operated Derails.

The invention provides an easily manufactured hand-operated sliding type derail, as distinguished from pivoted derails in the 10 operation of which the derail block is inverted, specially suited for installation under variant conditions of track without requiring the precise location on the ties required for other sliding derails and also adapted to 15 be thrown by hand with the same ease and promptness as the smaller types of pivoted derails. The invention consists, to these ends, in the organization of base and derailing members and their several bearing elements according to the principles herein described and as exemplified in the accompanying drawings, wherein—

Fig. 1 is a side elevation of the preferred form of the invention in the closed position,

Fig. 2 the same partly in section showing the derail block in the act of removal from the rail,

Fig. 3 a partial end view of the forward bearing,

Fig. 4 a side elevation of the derail block in its movement towards the open position,

Fig. 5—the same in its fully open position,
Fig. 6 a top plan of Fig. 1,

Fig. 7 a rear elevation thereof.

The base member is composed of two upright side wall portions 1 united by lower cross wall portions 2 and 3 (Fig. 2) and provided with exterior spike flanges 4 by means of which it is spiked to two adjacent 35 ties alongside the rail. The derailing member comprises a body 5 and a derail block 6 both formed of a single casting recessed on its under side for lightness and formed with a central downwardly open cavity 7 serving 40 as a handhold by means of which it is manually operated. Said cavity opens into the hollow interior of the derailing member so as to be self clearing of snow or water.

The body 5 of the derailing member is 45 carried in the open space between the side walls of the base, in forward and rear bearings on which it is movable toward and from the rail by a generally horizontal movement. The rear bearing is formed by a central web 50 or rib 8 depending from the rear part of

the derailing member and sliding by its lower curved edge upon a rounded bearing surface 9 formed on the rear cross wall 3. The rib is confined to this bearing by the two upstanding lugs 10 and 11, one of which is undercut so as to overlie a rail 12 on the side of the rib to keep the rear part of the derailing member against upward displacement. The forward bearing is formed by two laterally projecting studs 13 which slide 60 in grooves 14 formed in the inner faces of the walls of the base. When the derail block is moved from the position indicated in Fig. 5 toward the rail, the rib slides on its bearing 65 70 75 80 85 90 95 100 105 110 9 and the grooves 14 impart an upward inclination to the movement causing the block to swing in a vertical arc (of increasing radius) about said rear bearing as a center and such upwardly directed movement continues until the block reaches the extreme limit of its horizontal railward movement striking the side of the rail head, at which point each of the studs 13 registers vertically with an offset space or clearance 15, represented by a widening of each groove at its forward end (Fig. 2) so that the block can then drop, substantially vertically, onto the rail-head as indicated in Fig. 1. In this position the abrupt and substantially vertical face of the shoulder 16 prohibits a withdrawal of the block by any force applied thereto in a horizontal direction thereby compelling the derail block to be bodily lifted to the position indicated in Fig. 2 before it can be slid back away from the rail. Such upward movement of the derailing member, is however limited by the upper side of the grooves 14 which extend to the forward end of the base, the confines of such grooves thus serving to limit the vertical arc through which the derail block may swing. The vertical dimension of the offset spaces 15, however provides an adequate vertical movement of the block when in its forward position sufficient to permit it to drop to a firm bearing on the rail-head notwithstanding a considerable degree of misplacement of the guide box or base upon the ties, and the fact that the block swings about a pivotal axis furnished by the rear bearing which is at a considerable distance from the derail block (generally more than twice the distance of the pivot of common types of pivoted or swinging derails) insures that the bottom bearing surface of the derail

block proper will rest practically flat upon the tread surface of the rail-head, thus providing a proper bearing for the block notwithstanding imperfections of installation 5 or trackway. It will be apparent to those skilled in this art that the advantages accruing from the relation just described are not dependent upon the specific form of the front or rear bearing members, although the 10 combination of double forward bearings and a central single rear bearing as hereinabove described and shown in the drawings is found most satisfactory and constitutes a feature of the invention. The general type 15 of rib-form bearing herein described is also disclosed and claimed in a copending application.

The derail base above described is provided with a perforated locking ear 17 to 20 receive the hasp of a padlock, which, when inserted will cooperate with the abutment surfaces 18 and 19 on the derailing member to lock it in either of its extreme positions. It is also equipped with an attachment lug 25 20 for connection to a target stand operated by the derail. These details are optional but when the attachment lug is provided it is located sufficiently close to the level of the rear bearing so that the vertical movement 30 of the member will not tend to move the connecting rod 21 longitudinally thereby guarding against any restraint to the free descent of the derail block upon the derail or its upward movement therefrom.

35 Claims:

1. A derail comprising a base and a derailing member mounted thereon to be moved by hand substantially horizontally toward and from the rail and supported 40 upon forward and rear bearings, one of said bearings providing a pivotal axis upon which said member may swing in a limited vertical arc and the other terminating in an abruptly offset space located to permit abrupt 45 and substantially vertical descent of the derail block on its arrival at the limit of its horizontal railward movement.

2. A hand-operated derail comprising a base and a derailing member mounted thereon 50 upon a rear bearing providing a pivotal axis on which said member may swing in a limited vertical arc and a forward bearing having an abrupt and substantially vertical shoulder at the extreme position permitting

abrupt descent of the derail block on its arrival at the limit of its horizontal railward movement, and preventing withdrawal of said member by a horizontally directed force. 55

3. A hand-operated derail comprising a base and a derailing member mounted thereon upon a rear sliding bearing which provides a pivotal axis upon which said member may swing in a limited vertical arc, and upon a forward sliding bearing having an abruptly offset space and abutment surface 60 at its forward end permitting abrupt descent of the derail block on its arrival at the limit of its horizontal railward movement and compelling the block to be lifted vertically before it can be withdrawn from 65 the rail. 70

4. A hand-operated derail comprising a base and a derailing member mounted therein to move toward and from the rail and supported therein on forward and rear bearings, 75 one of said bearings having an abutment surface adapted to prevent withdrawal of the derail by a horizontally directed force.

5. A hand-operated derail comprising a base and a derailing member mounted thereon 80 on forward and rear bearings, one of said bearings being shaped to compel movement of the derail block in an inclined path to a point above the rail and then sharply downward upon the rail-head, and a handhold formed on said member above said bearing. 85

6. A hand-operated derail comprising a sliding type derailing member mounted on 90 bearings on a base and carrying a derail block, said bearing being shaped to compel railward movement of said member first to a position above and in contact with the side of the rail-head and then abruptly downward until the block seats on the rail tread. 95

7. A hand-operated derail comprising a base member and a derailing member mounted thereon on a rear bearing constituted by a longitudinal curved rib on one member 100 sliding on the other member and a forward bearing groove shaped to compel movement of the derailing member first to a point directly above the rail-head and in contact with the side thereof, and then abruptly downward onto the top of the rail-head. 105

In testimony whereof, I have signed this specification.

STANLEY W. HAYES.
